UNITED STATES PATENT OFFICE.

JOSEPH MANCINI AND JOSEPH MASTRICH, OF STAMFORD, CONNECTICUT.

RAIL-TRANSPORTING DEVICE.

Application filed July 7, 1924. Serial No. 724,721.

To all whom it may concern:

Be it known that I, JOSEPH MANCINI, a citizen of Italy, and JOSEPH MASTRICH, a citizen of the United States, both residing at Stamford, in the county of Fairfield and State of Connecticut, have invented certain new and useful Improvements in Rail-Transporting Devices, of which the following is a specification.

10 This invention relates to what may be conveniently termed a rail transporting device, that is, a device, which is adapted to hoisting and transporting a rail section from a point where it has been deposited to the 15 point to be laid in forming a railroad track.

What we aim to do is to provide a comparatively simple mono-rail carriage or truck which is constructed for travel over the portion of track already laid, together 20 with a novel hoisting device, and means for properly balancing the entire device, so that the entire operation can be carried out by approximately eight men. Heretofore, so far as we know, it has required approximately 25 eighteen men to carry out the operation, that is, where a heavy rail section has to be carried by the common tongs alone.

One feature of the invention is the relative co-action of the hoisting lever and rail 30 gripping tongs wherein the weight of the rail sections practically serves to hold the tongs closed.

Another feature of the invention is the novel fulcrum on the truck and the detachable rail hoisting and supporting lever, which is adapted to be adjustably connected therewith to vary the leverage and to relieve the workmen of undue strain.

The invention, of course, embodies other 40 features and advantages and these will be made apparent by the following description, and drawing.

In the accompanying drawing, forming a 45 part of this application, and in which like numerals are employed to designate like parts throughout the same:

Figure 1 discloses a front end elevation of the device, showing the method of use.

Figure 2 is a top plan view thereof.

50 Figure 3 is a side elevation of the same with the hoisting lever removed.

In carrying out the invention we employ a wheel supported truck or carrier, which 55 comprises an elongated solid body 1, of suitable material. This body has its under

side fashioned adjacent its opposite ends to accommodate grooved wheels 2, for reception on the track section T. Supported on top of the body is a sturdy bracket 3, which is provided with upstanding portions at the 60 upper ends of which are bearings 4. These bearings accommodate the journals on the ends of a flanged roller 5. The roller serves a purpose to be hereinafter described. At its opposite ends, the body is provided with 65 suitably designed handles 6, by means of which is placed on or taken off of the track T. Furthermore, at its opposite ends, and on opposite sides it is provided with depending plates 7, which are provided with 70 polygonal openings for reception of the flat face end portion of the handles 8. It is to be noted that the handles are offset, in opposite directions with respect to the body to permit convenient manipulation of the device.

Adapted to cooperate with the aforesaid roller 5 is a lever which has an arched central portion 9, and a gripping handle 10. The under side of the arched portion is 80 formed with longitudinally spaced notches 11, which are adapted to be selectively engaged with the roller 5. That portion of the lever beyond the arch is upturned, as indicated at 12, to provide a stop. The portion between the stop and the arch is adapted to be inserted through the elongated looped portions 13 of the crossed handles of the rail gripping tong 14. The rail section to be lifted and engaged by the jaws of the tong is indicated by the reference character R.

In practice, the jaws of the tong are arranged to engage with the approximate center of the rail R so that the latter will be 95 more or less balanced while in transit. Assuming that the free end of the lever is in the approximate position shown in Figure 1, it will be seen that upon bearing down on the handle 10, the rail will be lifted. While the rail is held in suspension, the handles 8 are grasped by workmen on opposite sides of the truck and the latter is pushed along the track and the rail R is thus conveyed and carried to the desired point of deposit.

100 It is thought that the several features and advantages of the invention are apparent by now, and for that reason we do not think that it is necessary to go more into detail.

We claim:

1. A rail transporting device comprising a truck including a body provided with grooved wheels adapted to travel on the track, a bearing bracket carried by said body, a roller having journals rotatably received in the bearings of said bracket, a lever provided intermediate its ends with notches adapted to be selectively engaged with said roller, and means for pushing and balancing said trucks.
2. In a rail transporting device, a truck including an elongated body provided on its under side with centrally disposed grooved rollers adapted to travel upon a track, depending plates carried by said body and disposed adjacent the opposite ends thereof, said plates being provided with polygonal openings, flat faced handles fitted into said openings for pushing and balancing the

trucks, a bearing carried by the upper side of said body, and a flanged roller having journals rotatably received in said bearing.

3. In a rail transporting device, rail engaging tongs, the handles of which are provided between their ends with elongated slotted portions, and a lever adapted to have one end extended through said slotted portions, one end of the lever being upturned to provide a stop to prevent slippage of the prongs beyond the same, the intermediate portion of the lever being arched and provided on its under side with longitudinally spaced notches, and that portion of the lever beyond the arch being constructed to provide a handle.
